UNITED STATES PATENT OFFICE.

JOHN B. O'CONNOR, OF AURORA, ILLINOIS, ASSIGNOR TO LYON METALLIC MANUFACTURING COMPANY, OF AURORA, ILLINOIS, A CORPORATION OF ILLINOIS.

LOCKING MECHANISM FOR DOORS.

Application filed June 19, 1920. Serial No. 390,127.

To all whom it may concern:

Be it known that I, JOHN B. O'CONNOR, a citizen of the United States, residing at Aurora, in the county of Kane and State of Illinois, have invented a certain new and useful Improvement in Locking Mechanism for Doors, of which the following is a specification.

My invention relates to door locking mechanism and is especially useful in connection with cabinets, lockers and similar structures. One of the objects of my invention is to provide a structure having a self-latching liftable latch with locking mechanism so constructed that the lock proper may be set in locked condition and the key withdrawn prior to the closing of the door; after which the closing of the door will automatically cause the latch to take hold and thereafter prevent the door from opening. Another object is to provide locking mechanism having a handle slidably mounted on the door for releasing the latching mechanism and locking mechanism, carried on or movable with the handle. Another object is to provide a structure in which the latch is gravity operated and movable vertically and the lock includes a rotatable element having a locking arm or lever, the free end of the arm riding upon a ledge or bracket and the parts so arranged that a rotation of the plug in a direction to unlock the door tends to lower the free end of the arm, whereby the operator, by exerting a moderate rotary force on the key, will tend to lift the latch. Another object is to provide a structure in which there is a plurality of liftable latches spaced at intervals and operated from a common bar whereby the door may be secured at a plurality of points, and the latches released by a liftable and lockable handle. Still another object is to provide a sheet metal door and door frame, the door frame having an integral, countersunk stop strip to enable the front of the door to come flush with the front of the frame, thus rendering it difficult if not impossible to insert a prying tool for forcing the door open. In this connection, a further object of the invention is to provide slots in the countersunk stop strip, which slots receive the latching members, and thus enabling them to engage portions which are integral with the door frame itself.

I accomplish my objects by the mechanism 55 illustrated in the accompanying drawings, in which—

Figure 1 is an assembly view in perspective, showing the door partly open;

Figure 2 is a view from the inside of the 60 door;

Figure 3 is a vertical sectional view on the line 3—3 Figure 2;

Figure 4 is a plan section on the line 4—4 65 Figure 3;

Figure 5 is a plan section on the line 5—5 Figure 3;

Figure 6 is a sectional elevation on the line 6—6 Figure 2;

Figure 7 is a plan section showing the 70 countersunk stop strip of the door frame, together with one of the slots therein and the associated latch and related parts;

Figure 8 is a vertical section on the line 75 8—8 Figure 2;

Figure 9 is a vertical section on the line 9—9 Figure 8;

Figure 10 is a front view of the lock proper and the associated portion of the 80 handle;

Figure 11 is a plan section on the line 11—11 Figure 9;

Figure 12 is a sectional view on the line 9—9 Figure 8, but showing the locking arm 85 in unlocked position.

Figure 13 is a perspective view of one of the latches, this particular sample having the arm overlying the lift pin, by which all of the latches may be lifted;

Figures 14 to 17 are perspective views 90 from the inside of the door, showing the locking parts in various positions.

Like numerals denote like parts throughout the several views.

While this invention is not necessarily confined to lockers, cabinets, et cetera, of sheet metal, nevertheless, it has certain characteristics of particular advantage in such structures, and I have chosen to illustrate the invention as applied to a sheet metal structure. 95 In the form shown, the door frame 1 is an integral part of the front of the locker or cabinet. At one side it has hinges 2 for supporting the door 3 and at the opposite side has a stop strip 4, which is integral with it 100 and sufficiently countersunk to permit the surface of the door to come flush with the front of the main structure. This stop strip

has a number, for example three, slots 6 adapted to receive the latches 8. These latches are vertically movable and preferably gravity-operated and their front edge 5 is beveled to enable them to ride up over the lower edges of the slots as the door closes. When the door is fully closed, the latches which are notched on their under side, drop down and engage the metal at the lower 10 ends of the slots. The door, which is here shown to be of sheet metal, is reinforced by internal flanges 10 at top, bottom and hinged margin. At the free edge it is provided with a flange 12 which is offset from the extreme edge a distance equal to the width of the countersunk stop strip. The construction is illustrated in Figures 14, 16, and elsewhere.

This formation at the free edge of the 20 door not only produces a rigid construction, but the flange 12 also forms a backing or guide for the vertically-slidable latch bar 14. This bar by preference, extends throughout the greater portion of the height of the door, 25 and the latches 8 previously mentioned, are fastened to it. The bar is held in place by headed pins 15 fastened to the inside of the flange 12 and working in slots 16 in the latch bar, as shown in detail in Figure 6.

30 In practice, the bar is lifted by means of a lift pin 18, best shown in Figures 2, 8, 9, and 14 to 17. This pin projects through a slot 20 in the door to the under side of a lifter arm 21 rigidly fastened to the latch 35 bar and by preference forming an integral part of one of the latches, as shown in perspective in Figure 13. The lift pin is rigidly fastened to a plate 22 which forms part of the handle 24 as shown on a somewhat 40 increased scale and in section, in Fig. 8. The plate is guided in any suitable manner, for example, headed pins 26, the heads whereof lie against the inner surface of the door and the shanks whereof work in the vertical 45 slots 27. A portion 28 of the handle is thickened to form a suitable mounting for the lock proper.

It is desirable for my purpose to employ 50 a pin tumbler cylinder lock and as such locks are well known, it will be sufficient for the present purpose to say that the lock has a cylinder 30 in which is mounted a rotatable plug 31 having a key hole 32 for the reception 55 of the shank of a key 33. It will be understood that in locks of this type the key 60 cannot be withdrawn except when the plug is rotated to locked position and the plug cannot be rotated except by the insertion of a properly formed key. A locking arm 34 is fastened to the inner end of the plug in such manner that the arm rotates in a plane 65 parallel and adjacent to the inner surface of the door. This arm is enclosed within a housing 36 rigidly fastened to the inner side of the door. In the preferred construc-

tion, this housing encloses the locking arm on all sides as shown for example, in Figure 2 and Figures 14 to 17. This guards against access of a prying tool.

The locking arm is fastened to the rotary 70 plug in such position that when the plug is in locked condition the locking arm will stand vertically upright as shown for example in Figures 8 and 14. The top of the housing overlies the upper end of the locking arm so closely as to prevent it and the handle from rising. This prevents the handle from lifting the latches. When the plug is rotated 90° and brings the locking arm to horizontal position, the latches may be lifted. One of the peculiarities of my device 75 is that by rotating the key still further after the locking arm has reached the horizontal position (shown in dotted lines in Figure 9 and in full lines in Figure 15) it will tend to 80 lift the latches. This is due to the fact that its free end rides upon the bottom of the housing and as it cannot descend any farther, the rotation of the key tends to raise the opposite end of the arm and with it 85 the plug and parts connected thereto. Figures 12 and 16 show in full lines the position the parts will assume if the key is thus additionally rotated. However, it is not necessary to rotate the key after the locking arm 90 has reached horizontal position, for the operator may simply pull upward on the handle or pull upward on the key without rotating it any farther. An experienced operator 95 will frequently lift the latches by exerting 10 both a rotary and an upward pressure of the key with or without the assistance of an upward pressure on the handle. This releases the door with very little effort. It may thus be said that the torque of the key after 10 the parts are unlocked, contributes in the elevating of the latch bar and latches.

To summarize the operation of the parts:

If the locking bar 34 is in upright position, as it will be when the lock is in locked 110 position, it will prevent the rise of the handle by striking against the top of the housing and thus prevent the latch bar and latches from being lifted. To open the door the operator must first insert the key and then rotate the locking arm to unlocked position — that is, to horizontal position or approximately so. The handle is then free to be lifted and this may be accomplished either by pulling up on the handle or continuing to exert a rotary pressure upon the key or to pull upward upon the key, or a combination of these pressures. If the door is open the key may be rotated to put the lock 115 in locked condition and may be withdrawn prior to the closing of the door. If the door is then pushed shut the latches will first rise automatically and then drop into acting 120 position, after which the latches cannot again be raised from the outside of the 125 door. If the door is closed and the key is withdrawn, the latches will drop into acting position and the door will remain closed. If the door is then pushed shut the latches will first rise automatically and then drop into acting 130 position, after which the latches cannot again be raised from the outside of the door.

locker except by first rotating the locking arm 34 to unlocked position.

Having thus described my invention, what I claim as new and desire to secure by Letters Patent is:

1. Door locking mechanism having a latch mounted upon the door and movable with respect to it, a handle slidably mounted on the door for releasing the latch, and a lock 10 for preventing sliding movement of the handle, the lock being mounted in the handle and the latch being adapted to latch automatically as the door is closed and being movable independently of the handle to 15 permit automatic latching regardless of the position of the lock prior to the closure of the door.

2. Door locking mechanism having a gravity operated latch mounted upon the door 20 and slidable vertically upon it, a handle slidably mounted on the door and adapted to lift the latch for releasing the door, and a lock for preventing the sliding movement of the handle, the lock being mounted in the 25 handle and the latch being adapted to rise automatically as the door is closed and making one-way engagement with the handle whereby the latch may rise as the door is closed regardless of whether the lock is 30 locked or unlocked prior to the closure of the door.

3. Door locking mechanism having a gravity operated latch mounted upon the door and slidable vertically upon it, a handle 35 slidably mounted on the door and adapted to lift the latch for releasing the door, and a lock for preventing the sliding movement of the handle, the lock being mounted in the handle and movable vertically with it, the 40 latch being adapted to rise automatically as the door is closed, and the latch overlying a portion of the handle whereby it may rise as the door is closed even though the lock is locked.

4. In door locking mechanism a liftable latch, a slidable handle for lifting the latch and a lock mounted on the handle for preventing sliding movement of said handle.

5. In door locking mechanism a liftable 50 latch, a handle vertically slidable on the door for lifting the latch, a rotatable locking arm for preventing movement of the handle, and a lock for controlling the position of said arm.

6. In door locking mechanism a liftable 55 latch which is self latching, a slidable handle for lifting the latch, a lock mounted on the handle and including a rotatable plug, a locking arm fastened to the plug, and a stop on the door for preventing sliding 60 movement of the plug and handle when the arm is in locked position.

7. In door locking mechanism in which the door is locked by a liftable latch which is self latching, the combination, with such 65 latch, of a slidable handle for lifting the latch, a cylinder lock of the pin tumbler type mounted on the handle, the lock having a rotatable plug mounted in the cylinder, a locking arm secured to the plug and rotat- 70 ing with it, and a stop on the door for preventing sliding movement of the plug and handle when said arm is in locking position, said latch being capable of rising independently of the remainder of the locking 75 mechanism, whereby the locking arm may be placed in locking position either prior or subsequent to the closing of the door.

8. In door locking mechanism, the combination of a door, a door frame having slots, 80 a vertically movable locking bar mounted on the door, a plurality of bevel nosed latches mounted upon the bar in spaced relation, said latches being adapted to enter the slots in the door frame for engaging 85 it at a plurality of points, a vertically slid- 90 able handle mounted on the front of the door for lifting the latch bar, and a lock mounted on the handle for preventing movement thereof, the bar being vertically movable independently of the handle, whereby the bar and latch may rise automatically as the noses of the latches enter the slots of the door frame thus permitting the door to close and the latches to take effect even though 95 the lock be in locked condition before the door is closed.

9. In door locking mechanism in which the door is locked by a liftable latch, a 100 slidable handle for lifting the latch, a lock mounted on the handle and including a rotatable plug, a locking arm fastened to the plug, and a housing rigidly fastened to the inside of the door for preventing access to the arm, one portion of the housing constituting a stop for engaging the end of the 105 arm to prevent the lifting of the handle and latch.

10. In door locking mechanism in which the door is locked by a liftable latch, a 110 slidable handle for lifting the latch, a lock mounted on the handle and including a rotatable key-operated plug, a locking arm fastened to the inner end of the plug, and a shelf rigidly secured to the door beneath 115 the arm, the free end of the arm tending to descend when the plug is rotated in a direction to unlock the door whereby the rotary movement of the plug and arm tend to raise the plug, handle and latch.

In witness whereof, I have hereunto subscribed my name.

JOHN B. O'CONNOR.
